UNITED STATES PATENT OFFICE.

ARTHUR L. TUFVESON, OF TUSTIN, MICHIGAN.

SPRING-BOLSTER.

1,201,393.

Specification of Letters Patent. Patented Oct. 17, 1916.

Application filed May 17, 1915. Serial No. 28,666.

To all whom it may concern:

Be it known that I, ARTHUR L. TUFVESON, a citizen of the United States, residing at Tustin, in the county of Osceola, State of Michigan, have invented certain new and useful Improvements in Spring-Bolsters; and I do hereby declare the following to be a full, clear, and exact description of the invention, such as will enable others skilled 10 in the art to which it appertains to make and use the same.

This invention relates to improvements in wagon bolsters.

The principal object of the invention is to 15 provide a simple and cheap bolster which can be attached to the axle of any wagon, and which is resilient in its nature.

Other objects and advantages will be apparent from the following description when 20 taken in connection with the accompanying drawing.

In the drawing: Figure 1 is a rear elevation of the front bolster of a wagon made in accordance with my invention. Fig. 2 is 25 a rear elevation of the rear bolster of a wagon made in accordance with my invention. Fig. 3 is a vertical sectional view on the line 3—3 of Fig. 1. Fig. 4 is a vertical central longitudinal sectional view through 30 the front bolster.

Referring particularly to the accompanying drawing 10 represents the rear bolster of the wagon, which is provided with the standards 11. Secured to the bottoms of 35 the ends of the bolster are brackets 12, and disposed through these brackets are the short shafts 13, the ends of said shafts being turned upwardly and inwardly, as shown at 14. To these inwardly turned ends of the

shafts are loosely connected the opposite 40 ends of the longitudinally extending, and downwardly bowed springs 15. These springs are arranged in parallel relation, and have secured to their intermediate portions the plate 16, which is properly secured 45 to the axle 17 by the clips 18. Thus when downward pressure is exerted on the bolster the springs will tend to straighten out and swing the shafts on their pivots in the brackets. 50

The front bolster 19 is similar in construction to the rear bolster, except that the plate 20 is formed with a central opening 21 for the reception of the king bolt 22, which is passed through the fifth wheel, as usual. 55

What is claimed is:

In a wagon, a body bolster, shafts mounted adjacent the ends of the bolster at the underside thereof and projecting outwardly on each side of the bolster, the ends of the 60 shafts being bent upwardly and bent inwardly whereby their terminal portions lie adjacent the sides of the bolster, downwardly bowed springs having eyes at their ends engaging the inwardly turned ends of the shafts, said springs being located one on each side of the bolster, and a plate secured to the intermediate portions of the springs for attachment to the axle of the vehicle, said plate holding the intermediate portions 65 of said springs in fixed relation. 70

In testimony whereof, I affix my signature, in the presence of two witnesses.

ARTHUR L. TUFVESON.

Witnesses:

Mrs. C. E. PULLMAN,
H. C. GOLDSMITH.
